JULIUS V. MEYERING, OF CHICAGO, ILLINOIS, ASSIGNOR TO GRUBE-MEYERING TRUNK COMPANY, OF CHICAGO, ILLINOIS, A CORPORATION OF ILLINOIS.

GARMENT-SUPPORTING FIXTURE.

2,099,381.

Specification of Letters Patent.

Patented June 9, 1914.

Application filed December 26, 1913. Serial No. 808,777.

To all whom it may concern:

Be it known that I, JULIUS V. MEYERING, a citizen of the United States, and a resident of Chicago, county of Cook, and State of Illinois, have invented certain new and useful Improvements in Garment-Supporting Fixtures, of which the following is declared to be a full, clear, and exact description.

10 This invention relates to garment supporting fixtures for wardrobe trunks, and its principal object is to provide a jointed or hinged suit hanger support, with novel means for holding said support in extended and folded condition; another object is to provide an improved, strong and substantial garment supporting fixture, of simple and comparatively inexpensive construction. With these and other objects and advantages in view, this invention consists in the several novel features hereinafter fully set forth and claimed.

The invention is clearly illustrated in the accompanying drawing in which:

25 Figure 1 is a perspective view of a garment supporting fixture embodying the preferred form of the present invention; Fig. 2 is a detail vertical section taken on line 2—2 Figs. 1 and 3; Fig. 3 is a detail vertical section, taken on line 3—3 Fig. 2. Fig. 4 is a detail vertical section taken on line 4—4 Fig. 3, and Fig. 5 is a plan of a fragment of one supporting rod and an extension therefor.

35 In the embodiment of the invention illustrated in said drawing, 10, designates a frame member, which, in its preferred form, may consist of a flat bar, the ends, 11, of which may be bent at right angles to the rear connecting portion, 12, at corners 13, to form an open-front, three sided frame member, which may be made of suitable size to fit in an open front compartment of a wardrobe trunk. Holes 13^a are provided in the frame member 10, for receiving bolts or rivets for connecting the frame member to the walls of the trunk, in accordance with usual and well known practice.

40 Secured to the rear portion 12, of the frame member 10, and extending forward and parallel with the side members 11, are two rods 14, the forward ends of which are secured to brackets 15, one for each rod, that are bent up to form stirrup like structures. (See Fig. 2.) Each bracket 15, has a part

15^a which extends down from the rod 14, to which it is secured, is bent at right angles thereto as at 16, to form a horizontal portion 17, which extends to the wall of the trunk and is bent upward as at 18, to form an upright portion 19, the outer face of which (below the side member 11), is flush with the outer face of said side member, and said upright portion is bent in and up to rest against the inner face of said side member, 65 where the two are riveted or otherwise secured together. The upright portion 19, is provided with a hole for the reception of a bolt or rivet, whereby said upright portion may be fastened to the wall of the trunk. 70 Each stirrup like bracket provides a very strong and substantial support and brace member for carrying the forward end of the rod 14, and for maintaining the two rods 14, in spaced relation to each other. 75

To the forward end of each rod 14, is pivotally secured an extension, in the form of a rod 20, one rod, (as the one 20) preferably being formed with a tongue 20^a, at its extremity, fitting in a notch in the extremity 80 of the other rod, and a rivet or headed pin 21, extending through registering holes in said rods, provides the pivotal connection between them; the pins 21, are in alignment with each other and extend in a horizontal 85 direction to permit the extension rods 20, to swing through a vertical plane. Upward movement of the extension rods 20, is limited by the extremities of rods striking against the shoulders formed at the base of the 90 tongue 20^a, and notch, and the arrangement is such as to limit upward movement of the extension rods to a horizontal position, each in alignment with the rod to which it is pivoted. The outer ends of said extension rods 95 20, are preferably provided with shoulders 23, here shown in the form of cross pieces riveted or otherwise secured on the outer ends of the rods 20.

The rods 14, and their extensions 20, are 100 designed to support garment hangers 24, having notched members 24^a, that rest upon the rods, and said garment hangers are adapted to support garments in the usual manner; they may be pulled forward to rest 105 upon the extension rods 20, when it is desired to remove or replace garments and they are pushed back upon the rods 14, and into the compartment of the trunk before closing the latter.

Supporting means are provided for holding the extension rods 20, in horizontal or extended position, and as illustrated, a brace member, here shown in the form of a detent 5 or pawl 25, is pivoted to each extension rod 20, on a horizontal pin 26, located somewhat beyond the pivot pin 21. Preferably each extension rod is formed with a notch in its side for the reception of the end of the detent 10 or pawl, and the extreme end of the latter is rounded off to conform to the contour of the rod 20 (see Fig. 2), whereby the notched hanger members 24^a, may pass freely over said detents without striking 15 against them. The lower or free end of each detent 25, is formed with a notch 27, and is arranged to engage with the forward edge of the horizontal part 17, of the associated bracket 15, whenever the extension rod is 20 raised to horizontal position. (See Fig. 3.) The detent or pawl forms a brace between the rod and bracket for supporting said rod in its horizontal or extended position. Preferably the detent is of the gravity form, and 25 its lower end drops into engagement with the forward edge of the bracket when the extension rod is fully raised into its horizontal position. To lower the rod, the detent is first disengaged from the bracket, by 30 lifting its lower end, after which the detent slides back on the bracket as the rod is being lowered.

Means are provided for locking the extension rods in their folded or vertical position, 35 and thereby preventing any swinging thereof and consequent rubbing on the inner face of the wall of the opposite compartment of the trunk. As here shown said locking means comprises a spring 28, lying in the path of movement of the detent 25; its lower 40 end being riveted or otherwise secured to the bottom member 17, of the bracket, and its upper end being in position to be engaged and depressed by the detent whenever the 45 extension member has been swung down. A pin 29 is secured in a vertical member 15^a of each bracket in position to engage with the upper edge of the detent, when the latter is moved back into engagement with the 50 spring 28, and a notch 30, is formed in the upper edge of each detent at the proper place to receive the pin 29 whenever the extension rod has been swung down into its folded position. In moving back and forth 55 the detent rides up the spring 28, and its upper edge engages with the pin 29; and the parts are so located with respect to each other that the detent depresses the spring, and its notch receives the pin, whenever the 60 extension rod is lowered to its extreme lowermost position; the spring thereupon acts to hold the detent in locked engagement with the pin, thereby preventing accidental displacement of the extension rod. Very little 65 force is required to disengage the detent

from the pin, and it is disengaged by simply taking hold of the extension rod and swinging it upward.

More or less variation of the exact details of construction is possible without departing from the spirit of this invention, and I desire, therefore, not to limit myself to the exact form shown and described, but it is my intention to point out in the following claims all of the invention which I have disclosed herein.

I claim as new and desire to secure by Letters Patent:—

1. In a garment supporting fixture, a pair of spaced, hanger supporting members, each comprising a fixed hanger supporting rod and a movable hanger supporting rod, pivotally secured thereto at its forward end and adapted to be swung into alinement with the fixed rod and also at an angle thereto, 80 brackets for supporting the ends of the fixed rods to which the movable rods are pivoted, a brace member pivoted to each movable rod, and adapted to bear against an adjacent bracket when said movable rod is in alinement with the fixed rod, and locking means carried by said brackets for holding the movable rods in their angular position with respect to the fixed rods.

2. In a garment supporting fixture, a 95 hanger supporting member, comprising a fixed hanger supporting rod and a movable hanger supporting rod pivoted thereto, and capable of being moved into alinement with the fixed rod and also at an angle thereto, 100 a bracket supporting that end of said fixed rod to which the movable rod is pivoted, a brace member to lock said movable rod and adapted to bear against said bracket, whenever said movable rod is in alinement 105 with the fixed rod, and locking means carried by said bracket, coöperating with said brace member to lock said movable rod against displacement when in its angular position with respect to the fixed rod.

3. A garment supporting fixture, comprising a hanger supporting member, consisting of a fixed hanger supporting rod and a movable hanger supporting rod pivoted thereto at one end, and capable of being 115 swung into alinement with the fixed rod and also at an angle thereto, a bracket supporting that end of the fixedly supported rod to which the movable rod is pivoted, a brace member pivotally connected to the movable 120 rod and adapted to bear against said bracket whenever said movable rod is in alinement with the fixed rod, and a spring latch co-operating with the said brace member for locking said movable rod when in its angular 125 position with respect to the fixed rod.

4. A garment supporting fixture, comprising a supporting frame, having an open side, a pair of hanger supporting members, spaced apart and away from the sides of 130

- said frame, each hanger supporting member comprising a stationary rod fixedly secured to said frame, and a movable rod pivoted to the stationary rod and adapted to be moved into alinement therewith and also at an angle thereto, brackets secured to the frame and supporting the forward ends of the stationary rods, and brace members, one for each movable rod and pivoted thereto, 5 said brace members being adapted to bear against said brackets whenever the movable rods are in alinement with the stationary rods, but operable independently of each other.
- 10 5. A garment supporting fixture, comprising a supporting frame, having an open side, a pair of hanger supporting members, spaced apart and away from the sides of said frame, each hanger supporting member comprising a stationary rod fixedly secured to said frame, and a movable rod pivoted to the stationary rod and adapted to be moved into alinement therewith and also at an angle thereto, brackets secured to the frame and supporting the forward ends of the stationary rods, brace members, one for each movable rod and pivoted thereto, 15 said brace members being adapted to bear against said brackets whenever the movable rods are in alinement with the stationary rods, but operable independently of each other, each brace member having a notch in one edge, pins, one secured to each bracket and lying in the path of movement of a brace member, and springs, one lying in the path of movement of a brace member, and operating to yieldingly press the same into locked engagement with the pin, 20 the notch receiving the pin.
- 25 6. A garment supporting fixture, a three sided supporting frame, brackets one secured to each side member of the frame near its end, each bracket having two upright portions connected by a transverse bottom portion, the upright portion, secured to the side member of the frame having a part flush with the outer face of the side member of the frame, whereby it may bear against the wall of a trunk and be secured thereto, a pair of spaced, jointed hanger 25 supporting members, paralleling the side members, and secured to the transverse member of the frame, and to the upper adjacent ends of the brackets, and brace members pivoted to the movable portions of the 30 jointed hanger supporting members, and adapted to bear against the brackets whenever said movable portions are in raised position in alinement with the fixed portions.
- 35 7. A garment supporting fixture, a supporting member, a pair of spaced, hanger supporting members, each comprising a hanger supporting rod fixedly mounted at both ends on said supporting member, and a movable hanger supporting rod pivotally secured to said fixedly supported rod at its forward end, and capable of being swung into alinement therewith independently of the other movable rod, and brace members, 35 one between each movable rod and the supporting member, said brace members being pivoted directly on said movable hanger supporting rods.
- 40 8. In a garment supporting fixture, a supporting frame, having an open side, a pair of hanger supporting members, spaced apart and away from the sides of said frame, each hanger supporting member comprising a stationary rod fixedly secured to said frame, and a movable rod pivoted to the stationary rod and adapted to be moved into alinement therewith and also at an angle thereto, brackets secured to the frame and supporting the forward ends of the stationary rods, brace members, one for each movable rod and pivoted thereto, 45 said brace members being adapted to bear against said brackets whenever the movable rods are in alinement with the stationary rods, but operable independently of each other, pins secured to said brackets and lying in the path of movement of said brace members, and springs secured to said brackets and adapted to engage said brace members, whenever the movable rods are folded down, and to press said brace members into locked engagement with said pins.
- 50 9. A garment supporting fixture, comprising a supporting frame, having an open side, a pair of hanger supporting members, spaced apart and away from the sides of said frame, each hanger supporting member comprising a stationary rod fixedly secured to said frame, and a movable rod pivoted to the stationary rod and adapted to be moved into alinement therewith and also at an angle thereto, brackets secured to the frame and supporting the forward ends of the stationary rods, brace members, one for each movable rod and pivoted thereto, 55 said brace members being adapted to bear against said brackets whenever the movable rods are in alinement with the stationary rods, but operable independently of each other, each brace member having a notch in one edge, pins, one secured to each bracket and lying in the path of movement of a brace member, and springs, one lying in the path of movement of a brace member, and operating to yieldingly press the same into locked engagement with the pin, the notch receiving the pin.
- 60 10. A garment supporting fixture, a three sided supporting frame, brackets one secured to each side member of the frame near its end, each bracket having two upright portions connected by a transverse bottom portion, the upright portion, secured to the side member of the frame having a part flush with the outer face of the side member of the frame, whereby it may bear against the wall of a trunk and be secured thereto, a pair of spaced, jointed hanger 65 supporting members, paralleling the side members, and secured to the transverse member of the frame, and to the upper adjacent ends of the brackets, and brace members pivoted to the movable portions of the jointed hanger supporting members, and adapted to bear against the brackets whenever said movable portions are in raised position in alinement with the fixed portions.
- 70 11. A garment supporting fixture, a supporting member, a pair of spaced, hanger supporting members, each comprising a hanger supporting rod fixedly mounted at both ends on said supporting member, and a movable hanger supporting rod pivotally secured to said fixedly supported rod at its forward end, and capable of being swung into alinement therewith independently of the other movable rod, and brace members, one between each movable rod and the supporting member, said brace members being pivoted directly on said movable hanger supporting rods.
- 75 12. A garment supporting fixture, a supporting frame, having an open side, a pair of hanger supporting members, spaced apart and away from the sides of said frame, each hanger supporting member comprising a stationary rod fixedly secured to said frame, and a movable rod pivoted to the stationary rod and adapted to be moved into alinement therewith and also at an angle thereto, brackets secured to the frame and supporting the forward ends of the stationary rods, brace members, one for each movable rod and pivoted thereto, 80 said brace members being adapted to bear against said brackets whenever the movable rods are in alinement with the stationary rods, but operable independently of each other, each brace member having a notch in one edge, pins, one secured to each bracket and lying in the path of movement of a brace member, and springs, one lying in the path of movement of a brace member, and operating to yieldingly press the same into locked engagement with the pin, the notch receiving the pin.
- 85 13. A garment supporting fixture, a three sided supporting frame, brackets one secured to each side member of the frame near its end, each bracket having two upright portions connected by a transverse bottom portion, the upright portion, secured to the side member of the frame having a part flush with the outer face of the side member of the frame, whereby it may bear against the wall of a trunk and be secured thereto, a pair of spaced, jointed hanger 90 supporting members, paralleling the side members, and secured to the transverse member of the frame, and to the upper adjacent ends of the brackets, and brace members pivoted to the movable portions of the jointed hanger supporting members, and adapted to bear against the brackets whenever said movable portions are in raised position in alinement with the fixed portions.
- 95 14. A garment supporting fixture, a supporting member, a pair of spaced, hanger supporting members, each comprising a hanger supporting rod fixedly mounted at both ends on said supporting member, and a movable hanger supporting rod pivotally secured to said fixedly supported rod at its forward end, and capable of being swung into alinement therewith independently of the other movable rod, and brace members, one between each movable rod and the supporting member, said brace members being pivoted directly on said movable hanger supporting rods.
- 100 15. A garment supporting fixture, a supporting frame, having an open side, a pair of hanger supporting members, spaced apart and away from the sides of said frame, each hanger supporting member comprising a stationary rod fixedly secured to said frame, and a movable rod pivoted to the stationary rod and adapted to be moved into alinement therewith and also at an angle thereto, brackets secured to the frame and supporting the forward ends of the stationary rods, brace members, one for each movable rod and pivoted thereto, 105 said brace members being adapted to bear against said brackets whenever the movable rods are in alinement with the stationary rods, but operable independently of each other, each brace member having a notch in one edge, pins, one secured to each bracket and lying in the path of movement of a brace member, and springs, one lying in the path of movement of a brace member, and operating to yieldingly press the same into locked engagement with the pin, the notch receiving the pin.
- 110 16. A garment supporting fixture, a three sided supporting frame, brackets one secured to each side member of the frame near its end, each bracket having two upright portions connected by a transverse bottom portion, the upright portion, secured to the side member of the frame having a part flush with the outer face of the side member of the frame, whereby it may bear against the wall of a trunk and be secured thereto, a pair of spaced, jointed hanger 115 supporting members, paralleling the side members, and secured to the transverse member of the frame, and to the upper adjacent ends of the brackets, and brace members pivoted to the movable portions of the jointed hanger supporting members, and adapted to bear against the brackets whenever said movable portions are in raised position in alinement with the fixed portions.
